UNITED STATES PATENT OFFICE.

LOUIS STEINBERGER, OF BROOKLYN, NEW YORK.

SELF-COOLING STRAIN INSULATOR.

1,406,696.

Specification of Letters Patent. Patented Feb. 14, 1922.

Application filed October 12, 1918. Serial No. 257,864.

To all whom it may concern:

Be it known that I, LOUIS STEINBERGER, a citizen of the United States, and a resident of the borough of Brooklyn, county of 5 Kings, State of New York, have invented certain new and useful Improvements in Self-Cooling Strain Insulators, of which the following is a specification.

My invention relates to a strain insulator 10 so constructed as to be self cooling when the interior of the same becomes heated electrically.

One of the objects of my invention is to provide a self cooling strain insulator. Another 15 object is to provide means for ventilating the interior of a strain insulator. Another object is to provide a strain insulator, the strain members of which are so arranged as to surround the ventilating conduit passing through the insulator body. Another 20 object is to provide a strain insulator provided with strain members embedded within the central portion thereof and arranged adjacent to a conduit passing through the central portion of the insulator. Other 25 objects will appear from the specification and claims.

Referring to the drawings:

Fig. 1 is a vertical section through the 30 central portion of my improved insulator, the section also passing through one of the strain members, portions of the insulator being shown in elevation.

Fig. 2 is a section on line 2—2 of Fig. 1. 35 It is well known that in actual operation the insulating material, especially at the central portion of the insulator, becomes heated and thereby the insulator loses its efficiency. In other words, its efficiency is lowered. If the heat is permitted to continue for a certain period the destruction of the insulator will inevitably follow.

The present invention is applicable to all insulators but especially to strain insulators 45 and the insulator structure is so formed that the central portion thereof which heats rapidly, is provided with ventilating means, permitting the passage of the cool air therethrough and the exit of the hot air. As the 50 ventilating means provide for the dissipation of the heat generated within the body of the insulator maximum efficiency of the structure is maintained at all times.

It is desirable to keep the central portion 55 of the insulator body which is adjacent the strain members as cool as possible, other-

wise the insulating material when heated will so change in structure that the strain members will gradually move towards each other, and it is obvious that as they so move 60 the electrical value of the insulator is decreased. If the heating is continued a sufficiently long time without cooling there is danger of the two strain members contacting with each other, thereby creating a short 65 circuit which would result in the breaking down of the entire insulator.

I will now describe the preferred form of insulator embodying the invention hereinabove referred to. 70

Referring to the drawings, in which the same reference character indicates the same part in the several views:

A is an insulator the body of which may be formed of any suitable insulating material, but I prefer to use the insulating material known in the art as electrose. B is the integral strain member made of metal and C is a two-part strain member also made of metal, which is provided with the well 75 known means for connecting the two parts together, namely, one of the projecting ends 10 of the strain member is provided with screw threads which engage the screw threads in the socket 11 of the removable 80 portion of the strain member. The sleeve 12 is screw threaded to the other projecting end 10' of the embedded portion of the strain member and to the abutting end 13 of the removable portion of the strain member. This means of connecting the two-part 85 strain member so that said parts may also be removed, are well known in the art and therefore do not require a general description. 90

The strain members are also of the type invented by me and consist of ring shaped portions 20 and 30, said rings bridging the upright portions respectively of the two strain members. The body portion of the 100 insulator is molded about the strain members after they have been centered with respect to each other, bringing the ring portions of each insulator opposite each other so that the rims of the ring portions will be 105 in direct alignment, leaving a uniform space between the rings. The body of insulating material is molded about the assembled interlocked strain members so as to form a shape as shown in the drawing, in which 110 the insulating material is molded around the leg portions of each strain member to form

projections 25, 26, 27, (the fourth not shown in the drawing) and there is also a central, radially projecting flange 50 extending from the insulator.

5 A central opening or conduit 60 is formed through the body of the insulator, said conduit continuing through the ring portions of the embedded strain members. In forming the conduit care has to be taken to provide a sufficient thickness of insulating material around the inner surfaces of the rings.

10 As will be seen, the centrally arranged role passing through the body of the insulator and through the strain members permits of 15 the ready ventilation of the insulator when it is in actual operation and connected to a line, thereby tending to cool the central portion of the insulator, thus preventing its destruction by the generated heat.

20 It is to be understood that the above description and drawings are merely illustrative and the invention is not to be limited in any respect, except as defined in the subjoined claims.

25 Having now described my invention, what I claim as new and desire to secure by Letters Patent is:

1. A strain insulator provided with interlocking strain members provided with leg 30 and bridge portions, said insulator having a ventilating conduit extending therethrough in the same direction as the leg portions, said conduit passing through the bridge portions of the strain members.

35 2. An insulator, comprising a body of insulating material, strain members therefor, said strain members embodying side portions and central portions connecting the side portions together, said body of insulating material being provided with a ventilating conduit passing therethrough in a direction substantially parallel to the side portions of the strain members and situated therebetween, said conduit also passing

through the central portions of the strain 45 members.

3. An insulator consisting of a body of insulating material, strain members provided with leg and bridge portions embedded therein, said body of insulating material 50 being provided with a ventilating conduit passing through the said bridge portions of the strain members, said conduit also passing through the central portion of the insulator in a direction substantially parallel 55 to the leg portions of the strain members.

4. An insulator comprising a body of insulating material, strain members provided with side and central portions molded therein, said body portion being provided with a 60 ventilating conduit passing therethrough in a direction substantially parallel to the side portions of the strain members and situated therebetween and also passing through the central portions of the strain members. 65

5. In an insulator, a body of insulating material, interlocking strain members molded therein, the central portions of the strain members situated opposite each other, the said central portions being ring shaped, 70 and a ventilating conduit passing through the body of the insulator and also through the ring portions of the strain members.

6. In an insulator, a body of insulating material, interlocking strain members assembled therein, the central portions of the strain members situated opposite to each other, the said central portions being ring shaped, and a ventilating conduit passing through the body of the insulator and also 80 through the ring portions of the strain members.

In witness whereof I have hereunto set my hand at the borough of Manhattan, city and State of New York, this fourth day of October, 1918. 85

LOUIS STEINBERGER.
